UNITED STATES PATENT OFFICE.

JOHN LOVAS, OF ERIE, PENNSYLVANIA.

GUNNER'S SHIELD.

1,290,606.

Specification of Letters Patent.

Patented Jan. 7, 1919.

Application filed July 24, 1918. Serial No. 246,426.

To all whom it may concern:

Be it known that I, JOHN LOVAS, a subject of the King of Hungary, residing at Erie, county of Erie, and State of Pennsylvania, have invented certain new and useful Improvements in Gunners' Shields, of which the following is a specification.

This invention relates to improvements in gunners' shields and particularly to types 10 adapted for warfare.

The principal object of the invention is to provide an armor or shield which will effectively protect the upper part of a soldier from missiles directed by an enemy.

15 A further object is to provide a sliding shield through which the barrel of a gun is extended so that no aperture of considerable magnitude extends through the armor.

A still further object is to provide a substantial mount for the shield and gun which may be rotated in any given direction when 20 in operation, and which may be readily transported from place to place as may be desired.

25 These and other like objects are attained by the novel construction and combination of parts hereinafter described and shown in the accompanying drawings, forming a material part of this disclosure, and in which:—

30 Figure 1 is a perspective view showing a shield made in accordance with the invention.

Fig. 2 is an enlarged perspective view showing the head and engaging means by 35 which a gun is secured to the mount.

Fig. 3 is a vertical sectional view taken substantially through the center line of the shield, showing the gun and mount in side elevation.

40 Fig. 4 is a horizontal sectional view taken on line 4—4 of Fig. 3.

Fig. 5 is an enlarged fragmentary sectional view taken through a portion of the extreme front edge of the shield, and

45 Fig. 6 is an enlarged fragmentary vertical sectional view taken through the upper portion of the gun mount.

The device consists essentially of a pair of rectangular armor plates 10 and 11, 50 spaced at the rear and converging toward the front point 12, where they are firmly secured together, peep holes 13 being provided in the plates.

Attached to the apex, or point of convergence of the plates, is a vertical casing 14 having an open slot 15 at its front, through

which the muzzle 18 of the gun 19 projects, the same being provided with a front sight 20 as is usual. This gun projects through an opening 21, formed at the intersection of the 60 side plates 10 and 11, and slidably arranged within the casing 14, is a bar 23 through which the barrel passes, having an opening 24 in alignment with the gun sight 20 so that the gun may be sighted in the usual manner. 65

The bar 23 is held substantially central in its normal condition by a pair of opposed, upper and lower helically coiled springs 26, operable within the casing, but which permits the sliding bar 23, together with the inserted gun barrel, to be moved vertically within desirable limits. Joining the sides 10 and 11 are roof plates 27 and 28, whereby the structure is held rigidly together and which also prevents bullets or missiles from 70 dropping vertically to the damage of the operator. 75

Secured interiorly of the guard plates near their intersection are brackets 30 rigidly engaged with a semi-conical, hollow, cup-like 80 element 31, resting upon a similar reversed element 32, provided with lugs 33 at its bottom, and in which, pivotally engaged by the pins 34, are the legs or supports 35, provided with spurs 36 at their lower ends so as to 85 prevent the same from slipping.

Formed interiorly of the semi-conical element 32, is a raised hub 38, bored to receive a spindle 39, extending downward from the upper element 31, so that the elements 31 and 90 32 may be rotated, one relatively to the other and prevented from moving laterally, the elements contacting on their juxtaposed edges. Extending centrally upward from the element 31 is a pair of lugs 40 and connected therein, by the pin 41, is a downward extending lug 42, formed with a head 43 having a flat top 44, on which are positioned engaging lugs 45, adapted to receive the barrel of the gun and hold it firmly 95 100 in an engaged position.

When it is desired to operate the apparatus, the spurs 36 are positioned so as to rigidly engage with the soil or other foundation, while the soldier is positioned between 105 the armor plates 10 and 11 below the roof 27 and 28, the gun entered underneath the hook-like lug 45 and through the openings 21 into the sliding bar 23, whereupon the gun may be maneuvered within the opening 21 and sighted through the opening 24 within the bar 23, the act of raising or depressing the 110

muzzle of the gun being permitted due to the hinge pin 41 and it will be obvious that the entire upper structure may be turned, the spindle 39 being rotatably mounted within 5 in the extending hub 38, while contact of the elements 31 and 32 maintain the upper elements of the structure in an essentially rigid position, permitting the gun to be used in the ordinary manner.

10 Having thus described my invention what I claim as new and desire to secure by Letters Patent, is:

1. A gunner's shield comprising a pair of armor plates spread at the rear and attached 15 at their converging front edges, and armor roof plates rigidly engaged with said side armor plates, said first plates having an elongated opening at their converging edges, a casing attached over said opening, a bar 20 slidably engaged in said casing, said bar having openings through which the barrel of a gun may be passed, and an opening through which the gun may be sighted, and means in said casing for holding said bar in 25 a normally central position.

2. In a gunner's shield, the combination 30 with a triangular armor plate structure having an open base and an armor plate roof combined therewith and a slotted casing attached to the point of convergence of the plates of said structure, of a tripod stand by which said armor plates are supported, a

head pivotally engaged at the upper portion of said stand, means on said head by which a gun may be secured thereto, the 35 muzzle of said gun passing outward through an opening formed in the casing of said triangular shield, a perforated bar engageable with the muzzle of the gun, means for permitting said bar to move vertically whereby the main opening in the shield by means of said bar is closed, apertures in said bar through which said gun may be inserted and sighted, and means formed in said stand 40 permitting the upper portion to be rotated with relation to the lower portion.

3. In a gunner's shield, the combination with a pair of opposed armor plates converging at their front edges and having 45 openings through which a gun may be inserted, of a sectional base comprising a rotating upper element, a plurality of lugs hingedly attached to a tripod and connected to the lower base, a hub extending within the lower element of said base, a spindle 50 formed with said upper element extending into said hub whereby it is rotatably engaged, a gun support head pivotally engaged with said upper element, and means on said head whereby a rifle may be secured.

In testimony whereof I have affixed my signature.

JOHN LOVAS.

Copies of this patent may be obtained for five cents each, by addressing the "Commissioner of Patents, Washington, D. C."
